UNITED STATES PATENT OFFICE.

THOMAS L. STURTEVANT, OF QUINCY, AND THOMAS J. STURTEVANT, OF WELLESLEY, MASSACHUSETTS, ASSIGNEES TO STURTEVANT MILL COMPANY, OF PORTLAND, MAINE, A CORPORATION OF MAINE.

COMBINED COOLER AND MUFFLER FOR GAS-ENGINES.

SPECIFICATION forming part of Letters Patent No. 784,191, dated March 7, 1905.

Application filed October 11, 1904, Serial No. 228,025.

To all whom it may concern:

Be it known that we, THOMAS L. STURTEVANT, residing at Quincy, and THOMAS J. STURTEVANT, residing at Wellesley, in the county of 5 Norfolk and State of Massachusetts, citizens of the United States, have invented certain new and useful Improvements in a Combined Cooler and Muffler for Gas-Engines, of which the following is a specification, reference being 10 had therein to the accompanying drawings.

This invention relates to a combined cooler and muffler for use in connection with explosion gas-engines of the character now extensively in use for driving motor-vehicles and 15 motor-boats; and the invention has for its object to provide a combined cooler and muffler which will be simple and compact in construction and efficient in use.

In the accompanying, Figure 1 is a broken-out longitudinal section of a combined cooler and muffler embodying the present invention, and Fig. 2 is an end view of the same looking from the right of Fig. 1.

Referring to the drawings, 12 13 denote two 25 headers between which extend two series of exposed or uninclosed tubes 14 15. The entrance-header 12 is provided with an opening 16 to receive the exhaust-pipe of the engine, said opening 16 communicating with a circular 30 chamber 17 and the latter in turn communicating with the outer series of tubes 14, which open into an annular chamber 17' in the header 13. The inner series of tubes 15 extend from the said chamber 17' to the chamber 18 of the 35 header 12, so that the gases flowing outward in the outer series of tubes 14 will flow inward through the inner series of tubes 15 on their way to the chamber of the muffler or muffling-chamber 19, which is provided with an outlet 40 20 for the final exit of the gases. The muffling-chamber is formed by the cylindrical wall or casing 21, which extends between the headers 12 13.

The desirability of a cooler through which 45 the exhaust-gases are passed on their way to the chamber of the muffler will be well understood by those familiar with explosion gas-engines, in that the cooler serves to reduce the

volume of the gases, and consequently the back pressure on the engine, and also extracts their 50 heat to such an extent that they do not flame, and if the tubes have sufficient cooling-surface unexploded gases passing from them into the muffler cannot be ignited by the exploded gases following. In the present construction 55 such cooler is afforded by the cooling-tubes 14 15, through which the gases are passed on their way to the chamber of the muffler.

To obviate any possible danger of the explosion of the exhaust-gases within the chamber of 60 the muffler, if by chance, as is often the case, the engine should "miss," and an unexploded charge of fuel be discharged into the muffler, a foraminous screen 22, of wire-gauze or other suitable material, (as a finely-perforated metal 65 plate,) is preferably interposed between the passage-way from the tubes 15 to the chamber of the muffler, thus forming the chamber 18, heretofore referred to, and from which the gases pass into the chamber of the muffler 70 through the said foraminous screen, and which latter will effectively prevent the entrance of flame from the cooling-tubes into the chamber of the muffler should the cooling-tubes not have sufficient surface to cool some very hot 75 gases below the ignition-point.

Owing to the fact that in this improved combined cooler and muffler the cooling-tubes are arranged to surround or encircle the muffler, so as to partly cool the exhaust-gases and 80 reduce the temperatures of the same below the ignition-point before they enter the latter, and also owing to the fact that the headers of the cooler serve also as headers for the muffler a very compact, efficient, and comparatively cheap combined muffler and cooler is 85 provided by the construction herein shown and described, and it has been found by practical tests that with this improved construction of cooler and muffler the exhaust of the 90 engine is almost noiseless and explosions of unused charges in the muffler are rendered practically impossible.

Having thus described our invention, we claim and desire to secure by Letters Patent— 95

1. A combined cooler and muffler for gas-

engines, consisting of the combination with a muffler or muffling-chamber, of an exposed cooler entirely outside of but adjacent to said muffler or muffling-chamber and through 5 which cooler the gases pass to the said muffling-chamber.

2. A combined cooler and muffler for gas-engines, consisting of the combination with a muffler or muffling-chamber, of an exposed 10 cooler through which the gases pass before reaching the muffler, and which cooler is disposed about and adjacent to the said muffler and discharges into the latter.

3. A combined cooler and muffler for gas- 15 engines, consisting of the combination with a muffler or muffling-chamber, of a cooler outside of but adjacent to said muffler or muffling-chamber, and a foraminous screen in the passage-way for the gases between the cooler and 20 muffler.

4. In a combined cooler and muffler for gas-engines the combination with a muffler, of a cooler comprising two headers and a series of exposed tubes communicating with said headers and between which headers the muffler or 25 muffling-chamber is also arranged.

5. In a combined cooler and muffler for gas-engines, the combination with a muffler, of a cooler comprising two connected headers having 30 passages between them, and between which headers the said muffler or muffling-chamber is also arranged, and a foraminous screen in the passage-way for the gases between the cooler and muffler.

35 6. A combined cooler and muffler for gas-engines, consisting of the combination with a muffler or muffling-chamber, of an exposed multitubular cooler surrounding and discharging into said muffler.

40 7. A combined cooler and muffler for gas-engines, consisting of the combination with a muffler or muffling-chamber, of a multitubular cooler surrounding the same, and a foraminous screen in the passage-way for the gases 45 between the cooler and muffler.

8. A combined cooler and muffler for gas-engines, consisting of the combination with two headers provided with chambers and between which headers is a muffling-chamber, 50 of two series of tubes one series of which connects the chambers of said headers and the

other series of which forms a communication between the chamber of one of said headers and the muffling-chamber surrounded by said tubes.

55 9. A combined cooler and muffler for gas-engines, consisting of the combination with two headers provided with chambers and between which headers is a muffling-chamber, of two series of tubes one series of which connects the chambers of said headers and the other series of which forms a communication between the chamber of one of said headers and the muffling-chamber surrounded by said tubes, and a foraminous screen in the passage-way for the gases between the cooler and muffler.

60 10. A combined cooler and muffler for gas-engines comprising two headers, an outer series of exposed tubes through which the exhaust-gases flow outward from the first header to the second, an inner series of exposed tubes through which the exhaust-gases return from the second header to the first, and an inclosed muffling-chamber entirely within the circle of 65 said tubes and between said headers, and into which chamber the gases are discharged from the inner series of tubes.

70 11. A combined cooler and muffler for gas-engines comprising two headers, an outer series of tubes through which the exhaust-gases flow outward from the first header to the second, an inner series of tubes through which the exhaust-gases return from the second header to the first, a muffling-chamber between 75 said headers into which the gases are discharged from the inner series of tubes, and a foraminous screen in the passage-way for the gases between the cooler and muffler.

80 12. A combined cooler and muffler for gas-engines, consisting of a series of exposed or uninclosed cooling-tubes, and a muffling-chamber adjacent thereto and into which the said cooling-tubes discharge.

85 In testimony whereof we affix our signatures 90 in presence of two witnesses.
